UNITED STATES PATENT OFFICE.

FREDERICK M. MUNROE, OF HUNTINGTON, NEW YORK.

SAFETY-RAZOR.

1,290,641.

Specification of Letters Patent.

Patented Jan. 7, 1919.

Application filed May 6, 1918. Serial No. 232,876.

To all whom it may concern:

Be it known that I, FREDERICK M. MUNROE, a citizen of the United States, residing at Huntington, in the county of Suffolk, 5 L. I., State of New York, have invented a new and useful Safety-Razor; and I do hereby declare the following to be a full, clear, and exact description of the invention, such as will enable others skilled in the art to which it appertains to make and use the same.

The present invention relates to certain new and useful improvements in safety razors, and has for its object to provide a device of this character which embodies novel features of construction whereby the blade is held securely in position when the razor is in use, although it can be quickly released when desired.

20 Further objects of the invention are to provide a device of this character which is simple and inexpensive in its construction, which can be easily manipulated, which is not liable to break or get out of repair, and 25 which has no fine or delicate parts which will be destroyed by rust or corrosion.

With these and other objects in view, the invention consists in certain novel combinations and arrangements of the parts as will 30 more fully appear as the description proceeds, the novel features thereof being pointed out in the appended claims.

For a full understanding of the invention, reference is to be had to the following description and accompanying drawings, in which:

Figure 1 is a side elevation of a safety razor constructed in accordance with the invention, portions being broken away and 40 shown in section.

Fig. 2 is a perspective view of the safety razor with the parts detached and separated from each other.

Fig. 3 is a side elevation of a modified 45 form of the safety razor.

Fig. 4 is a horizontal sectional view on the line 4—4 of Fig. 3.

Fig. 5 is a view similar to Fig. 1, showing a slight modification.

50 Corresponding and like parts are referred to in the following description and indicated in all the views of the drawings by the same reference characters.

Referring to Figs. 1 and 2 of the drawing, 55 which illustrate one embodiment of the invention, the numeral 1 designates a handle

which is reduced at its upper end and provided with a threaded stud 2. The stock or body of the safety razor is formed from a single piece of resilient sheet metal which 60 is doubled or folded upon itself at its middle portion, thereby providing a looped base 3 from which a pair of spaced and diverging spring arms 4 project. These arms 4 are provided at their outer ends with outwardly 65 extending wings 5 which are curved downwardly and have the usual guard teeth 6 at the edges thereof. The razor blade 7 may be curved or of the wafer type, being formed of thin resilient metal, and having cutting 70 edges 7^a at opposite sides thereof. This blade is clamped against the wings 5 of the base by means of a cap plate 8 which has a curvature corresponding to the curvature of the wings 5, and has a width slightly less 75 than that of the blade 7 so that the cutting edges of the blade will be exposed.

The wings 5 of the base each have a tongue stamped therefrom, said tongues being bent upwardly and shaped to provide oppositely 80 facing hooks 9. The blade 7 is provided with openings 10 corresponding to the hook members 9 and adapted to receive the same when the spring arms 4 are flexed to spring the wings 5 toward each other. Similar open- 85 ings 11 are provided in the cap plate 8, and said cap plate is also provided with longitudinally extending ribs 12 which are parallel to the openings 11 and positioned adjacent the outer edges of the respective open- 90 ings, said ribs having curved or inclined sides. When placing the blade 7 in position or removing it therefrom the spring arms 4 are pressed toward each other so that the hook members 9 can be inserted through or 95 withdrawn from the openings 10 and 11 of the blade 7 and cap plate 8, respectively. When the razor blade is clamped in position against the wings 5, it is flexed to conform 100 to the curvature thereof, as indicated by 100 Fig. 1, the spring tension of the blade serving to take up any looseness and prevent any possible play. After the razor blade and cap plate have been properly positioned upon the wings 5, the spring arms 4 are re- 105 leased and permitted to move apart, whereupon the hook members 9 are brought into a positive engagement with the cap plate 8, the noses of the hook members riding upon the inclined sides of the ribs 12 and coöperating therewith to provide a cam action 110 which insures that the cap plate and razor

blade will be tightly clamped in position. When the parts are thus assembled, as in indicated by Fig. 1, the device can be used for shaving with perfect safety, although the 5 blade and cap plate can be quickly removed by pressing the spring arms 4 toward each other and releasing the hook members 9. The parts can then be quickly and thoroughly cleansed and a dull blade replaced 10 by a sharp blade whenever necessary.

A slight modification is shown by Figs. 3 and 4, in which the handle and stock have an integral construction, being formed from the same piece of sheet metal. The sheet 15 metal blank from which the handle and stock are formed is doubled upon itself at its middle point, providing spaced and substantially parallel side bars 14 which are sufficiently long to provide a handle and 20 have the edge portions thereof curved inwardly toward each other at 14^a to provide rounded sides for the handle. The spring arms 4^a, corresponding to the spring arms 4 of the previous construction, are continuations 25 of the upper ends of the side bars 14, and carry the wings 5^a, exactly as in the previous instance. A cross bar 15 may connect the upper ends of the side bars 14 to provide a rigid construction for the handle, 30 although the spring arms 4^a are flexible and adapted to be moved toward each other as previously described. The blade 7 and cap plate 8 are held in position by the hook members 9^a of the wings 5, and these hook 35 members may have the nose portions thereof curved so as to spring over the ribs 12 of the cap plate 8. This interlocking connection between the ribs and the hook members may be advantageous in some instances, since it 40 would tend to prevent any possibility of the parts becoming accidentally disengaged.

A further modification is shown by Fig. 5, in which the cap plate 8 is entirely omitted and the blade 7^c initially curved and shaped 45 to fit against the wings 5 of the stock. The cutting edges 7^a of the blade are positioned over the guard teeth 6 of the stock, as in the previous instance, and a pair of longitudinally extending ribs 15 are pressed outwardly 50 from the razor blade 7^c. These ribs 15 have a spaced and parallel relation to the cutting edges thereof and serve as guards to protect the face and prevent the ends of the hook members 9^c from scratching the 55 skin. The hook members 9^c operate exactly as in the previous instance to hold the razor

blade in position, although they engage the razor blade directly instead of the cap plate. The razor blade is adapted to be applied to the stock or removed therefrom by flexing 60 the spring arms 4 inwardly to disengage the hook members 9^c from the razor blade, and with this modified construction there are really but two parts to the razor so that the construction thereof is simplified as much 65 as possible.

Having thus described the invention, what I claim as new and desire to secure by Letters Patent, is:—

1. A safety razor including a stock formed 70 with a base and spaced spring arms projecting from the base, the outer ends of the spring arms being flexible toward and away from each other and being provided with corresponding lateral wings which extend 75 in opposite directions and have guard teeth at their outer ends, oppositely facing hook members projecting from the wings, a wafer blade adapted to fit against the wings and formed with openings through which the 80 hook members are insertible when the spring arms are moved toward each other, and cam means coöperating with the hook members to clamp the blade tightly against the wings when the spring arms are released 85 and permitted to expand into operative position.

2. A safety razor including a stock formed with a base and spaced spring arms projecting from the base, the outer ends of the arms 90 being movable toward and away from each other and terminating in lateral wings which project in opposite directions and have guard teeth at their outer edges, oppositely facing hook members projecting from 95 the wings, a wafer blade fitted against the wings and formed with openings through which the hook members are insertible when the spring arms are moved toward each other, and ribs projecting outwardly from 100 the blade and having a cam action with the noses of the hook members to clamp the blade in position when the arms are released and permitted to spring apart.

In testimony whereof I have signed my 10 name to this specification in the presence of two subscribing witnesses.

FREDERICK M. MUNROE.
